UNITED STATES PATENT OFFICE.

MALCOLM MCKENZIE, OF PLAINFIELD, NEW JERSEY

METHOD OF EXTRACTING TURPENTINE AND OTHER PRODUCTS FROM WOOD.

No. 851,687.

Specification of Letters Patent.

Patented April 30, 1907.

Application filed April 21, 1906. Serial No. 313,083.

To all whom it may concern:

Be it known that I, MALCOLM MCKENZIE, a citizen of the United States, and a resident of Plainfield, in the State of New Jersey, have invented certain new and useful Improvements in Methods of Extracting Turpentine and other Products from Wood, of which the following is the specification, reference being had to the accompanying drawing, forming a part hereof.

The invention relates to the extraction of turpentine and other products from wood by subjecting same to the action of a bath of rosin or similar substance heated to a relatively high degree of temperature.

Heretofore it has been customary to assist the separation of the turpentine from the bath by introducing steam directly into the vessel or retort in which the wood was being treated and then collecting and condensing the escaping volatile product or products. It has been found impossible, however, by this method, to extract the maximum quantity of turpentine or other products from the wood or to separate same from the bath, and the process is also objectionable as it may injure the fiber of the wood.

The object of this invention is to provide a method whereby not only the maximum amount of turpentine and other products may be extracted from the wood, but whereby a larger amount of turpentine may be separated from the bath and recovered, and whereby the wood may be treated without injuring its fiber or texture or impairing its use as lumber after it has been treated.

The accompanying drawing, which is partly in elevation and partly in section, discloses one form of apparatus for practicing the method.

As such apparatus is set forth and claimed in my copending application, Serial No. 293,920 for Letters Patent covering such apparatus no description thereof is necessary further than to illustrate properly the operation of the present method.

In the accompanying drawing *a* represents a vessel provided with suitable doors *b* and *b'* to permit it to be opened for the purpose of charging and discharging the wood and preferably provided with a fire box *d'* to assist in bringing the bath to the desired temperature. A second vessel *c* independent of the vessel *a* is provided with the usual dome *e* and worm *f* of an ordinary still. This vessel may also be provided with

a fire box *d* to aid in heating the rosin prior to beginning the circulation thereof. Communication is established through a pipe *g* between the lower portion of the vessel *c* and the vessel *a*, which pipe passes through a suitable heater *i* by which the bath can be reheated and brought to the desired temperature as it passes from the vessel *c* to the vessel *a*. The pump *h* is connected with the pipe so that the circulation between the two vessels may be maintained. Branches *g'* and *g''* provided with cocks *g³*, *g⁴* and *g⁵* communicate respectively at the top and bottom of the tank or vessel *a* with perforated distributing pipes *k* and *k'*. The branches *g'* and *g''* are likewise connected with the vessel *c* by extensions *g⁶* and *g⁷* respectively, such extensions being provided with cocks *g⁸* and *g⁹* respectively. The provision of the branches *g'* and *g''* of the pipe *g*, their extensions *g⁶* and *g⁷* and the several cocks referred to, are for the purpose, as will be readily understood, of permitting the direction of movement of the bath through the vessel *a* to be reversed.

The vessel *c* is provided in its lower portion with a perforated distributing pipe *l* through which a suitable substance preferably steam can be admitted to the bath as it lies in the vessel *c* for the purpose of facilitating the separation of the turpentine or other products.

In the practice of the method as embodied in the apparatus shown in the drawing, the closed vessel *a* is partly filled with wood, suitably divided to permit the permeation of the bath throughout the mass and the vessel *a* is then completely filled with rosin, or similar substance, at a temperature varying approximately from 340° F. to 380° F. usually nearer 380° F.

After the wood has been subjected to the action of this bath for a suitable length of time the bath or a portion of the bath is removed to the vessel *c* by means of the pump *h* and the pipes going from the vessel *a* to the vessel *c*, where it is agitated and cooled by some suitable means as steam or other gaseous fluid. If the cocks *g³*, *g⁵*, *g⁹* are opened and the other cocks are closed, the heated rosin will leave the tank *c* through the pipe *g* and enter the vessel *a* through the pipe *k* and will be returned to the vessel *c* through the distributing pipe *g⁷* while if the cocks *g⁴*, *g⁵* and *g⁹* be opened and the other cocks closed the rosin will leave the tank *c* through the pipe *g* and enter the tank *a* through the dis-

tributing pipe k' and will be returned to the vessel c through the distributing pipe k and the branch g^o .

As the rosin is pumped from the tank c where it has been agitated and cooled it may be forced through the heater i , so that the temperature of that portion of the bath which has been in the vessel c is restored to the predetermined temperature of the bath c in the vessel a prior to entering the same. Consequently the temperature of the bath in the vessel a may be maintained at an even temperature. This is important, because if the temperature of the material forming the bath is allowed to vary even a few degrees within the vessel a it may have a very deleterious effect upon the wood being treated, since the high temperature at which the bath is maintained renders the wood peculiarly susceptible to changes in temperature and only a slight variation is often sufficient to injure and in some cases to destroy the texture and quality of the wood and render it unavailable for further use. Furthermore, changes in temperature causes the wood to alternately expand and contract which interferes with the extraction of the turpentine and other products contained in the wood and such changes in temperature, if considerable, will not only interfere with, but will sometimes prevent any further extraction from the wood whatsoever. It is also possible to maintain the temperature within the vessel a at a higher point than would be possible were steam or other substance admitted directly into the vessel a , which higher temperature in many cases increases the extraction of desirable products from the wood. The steam or other cooling substance which is supplied to the bottom of the vessel c through the pipe l , not only causes a violent agitation of the portion of the bath contained therein, but also causes a reduction in the temperature thereof, such reduction often amounting to as much as 30 or 40 degrees. This agitation of the bath together with the considerable reduction in temperature causes the volatile products contained in the rosin to be given off, which are then collected and condensed in the usual well known manner. A portion of the bath is thus constantly renewed or rejuvenated so to speak, by having the volatile products removed therefrom which renders it more active in extracting further products from the wood and the same bath is thus used over and over again and the process is continuous.

Although it is old in the art to use steam for agitating a bath, yet, so far as I am aware, I am the first to discover a process providing for the cooling of a portion of the bath and also providing for the maintaining of that portion of the bath in immediate contact with the wood at an even temperature,

thereby extracting the greatest possible quantity of volatile products from the bath and from the wood and at the same time protecting the wood from injury due to variations in temperature. I am also the first, so far as I am aware to provide a method whereby the temperature of the bath may be continuously maintained at or almost at the critical or destructive temperature of the substance constituting the bath.

It is evident that various substances, other than rosin, may be used as the material of the bath such as various oils and hydrocarbons, and I do not intend to limit my process solely to the use of rosin as the material of the bath, but I have mentioned only rosin because it is evident, that whatever other substance is used as a bath, the constant exudation of rosin from the wood will speedily convert the bath originally used into a rosin bath.

I claim as my invention:

1. The method of treating wood which consists in subjecting the wood to the action of a bath in a suitable closed vessel, removing the bath and the extracted products to a separate vessel and agitating and reducing the temperature of the same to remove the extracted products by injecting a gaseous fluid, then reheating the bath to its former temperature and returning the same to the vessel containing the wood.

2. The herein described method of treating wood which consists in subjecting the wood to the action of a suitable bath, removing portions of the bath and the extracted products, reducing the temperature of such removed portions to extract the desired products unchanged and then returning the same to the bath.

3. The method of treating wood which consists in subjecting the wood to the action of a bath, continuously removing a portion of the bath and the products contained therein, agitating and cooling such removed portions so as to extract the desired products unchanged and then returning said portion to the original bath.

4. The method of treating wood which consists in subjecting the wood to the action of the bath, continuously removing a portion of the bath and the contained products, agitating and cooling such removed portion by steam to extract the desired products, then reheating such removed portion of the bath to its original temperature and returning the same to the bath.

This specification signed and witnessed this 30th day of March, A. D. 1906.

MALCOLM MCKENZIE.
